UNITED STATES PATENT OFFICE.

CHAUNCEY D. BRADT, OF GREEN ISLAND, NEW YORK, ASSIGNOR TO
GEORGIANNA BRADT, OF SAME PLACE.

MACHINE FOR CUTTING AND ASSEMBLING TICKETS.

SPECIFICATION forming part of Letters Patent No. 623,649, dated April 25, 1899.

Application filed December 17, 1898. Serial No. 699,541. (No model.)

To all whom it may concern:

Be it known that I, CHAUNCEY D. BRADT, of the village of Green Island, Albany county, and State of New York, have invented a new 5 and useful Mechanism for Cutting and Assembling Color Tickets, of which the following is a specification.

My invention relates to a mechanism by which strips of cardboard or paper upon one 10 side of which colors are displayed are cross-cut to form color tickets and also to a coöperating mechanism whereby as the tickets are cut from the strips they are assembled and arranged for application and use in a machine 15 by which they are attached to sample cards.

Accompanying this specification to form a part of it there are seven plates of drawings, containing eighteen figures, illustrating the 20 application of my invention, with the same designation of parts by letter reference used in all of them.

Of the illustrations, Figure 1 is a front elevation of the machine. Fig. 2 is a side elevation of the machine. Fig. 3 is a vertical 25 section taken on the line $x'x$ of Fig. 1. Fig. 4 is a top view of the inclined table, at the lower edge of which the strips are cross-cut, showing also a top view of the ticket-assembling mechanism, with the table shown as 30 broken apart horizontally. Figs. 5 and 6 are cross-sections taken on the line x^2x^3 of Fig. 3, that one of these sections shown at Fig. 5 illustrating the cutting-knife as down and that one of them shown at Fig. 6 illustrating 35 the cutting-knife as raised and broken off at the end which is opposite to that at which it is hinged to the machine. Fig. 7 is a side elevation of the hinging connection by which the cutting-knife attaches to the side of the 40 machine, with the parts in this illustration shown in a larger size than in the other figures. Fig. 8 is a top view of the gage. Fig. 9 is a section taken on the line x^3x^3 of Fig. 7. Fig. 10 is a perspective of one of the partitions which when in position are used to form 45 the chutes by which the tickets, after having been cut, are in their descent guided into the assembling-holders. Figs. 11 and 12 show detached parts of the assembling mechanism. Fig. 13 shows as detached one of the clamping-springs by which the chute-forming par-

titions of the assembling mechanism are adjustably attached. Fig. 14 shows one of the strips from which the tickets are cut. Fig. 15 shows one of the tickets cut from the strip. 55 Fig. 16 shows one of the guide-plates by which the strip-chutes are adjustably formed in the table and through which chutes the strips descend to where they are cut by the knife; and Fig. 17 shows another form of these plates 60 designed for the same purpose as those which are shown at Fig. 16, but which are used at the lower ends of the chutes. Fig. 18 represents in perspective and in a larger size than in the other figures a part of the inclined table 65 on which the strips are first placed, showing also one of the chutes formed therein by inserting guide-plates in the slots formed in the table.

The several parts of the mechanism thus 70 illustrated are designated by letter reference, and the function of the parts is described as follows:

The letters F designate the frame of the machine, and T an inclined table upon which 75 the strips are placed to be cut. This table at its lower end, as indicated at t^2 , is hinged to the frame-top at the front of the latter, and at its rear upper end this table is at t^3 adjustably connected with the rear of the frame at 80 its top by means of a bracket t^4 , which is horizontally slotted at t^5 and is projected from the under surface of the table T, at each side of the latter, with ears e formed on the upper end of each of the two upright branches of 85 the frame at the rear of the machine (there being but one of these uprights and one of these ears shown) and a pin passed through the ears e of each of the rear frame parts and the slot of one of the intermediately-placed 90 brackets t^4 .

The letter f^2 designates a turnbuckle formed on the rear upright of the frame part below where the latter is branched to support the rear end of the table T, at each side of the 95 latter, and by which turnbuckle the rear part of the frame is lengthened or shortened to vary the inclination of the table T.

The table T has upon one of its side edges an upwardly-projected side strip t^7 , and the 100 letters P designate bars of metal, which at regular intervals of spacing are let into the

table-top, so as to not project above the upper surface of the latter and as placed in the table to be at right angles to the inner vertical face of the side strip t^7 . Each of these bars P is constructed with slots p^2 , arranged to be vertically in line with each other and parallel to the inner vertical edge of the side strip t^7 . These bars are divided off into 10 inches, there being preferably twelve slots in each lineal inch of each of the strips P.

The letters p^3 designate guide or chute-forming plates, which are used in connection with the slots in the bars P to produce slide-passages for the strips O², from which the tickets O³ are to be cut. Each of these plates p^3 , as shown at Fig. 16, has on what is its bottom edge when in position in the table a projection p^4 and also an upper part p^5 , whereby each of the plates may have their projections 15 entered in one of the slots p^2 of one of the bars P, with the guide edges p^5 of the plates in vertical alinement with each other and in parallel alinement with the inner vertical face of the strip t^7 , these plates p^3 being employed 20 to form the upper parts of the strip chutes or guides C in the table T and in which the strips O² descend to be cut.

The plates having the form shown at Fig. 17 and designated at P⁵ are each used to produce 25 the side boundaries of the strip chutes or slideways at their lower ends as formed on the table T for the descent of the strips from which the tickets are cut. These plates P⁵ are made longer than the plates p^3 , and they 30 are each provided with a downward projection p^6 at each end, whereby either of the projections can be inserted in that one of the slots in the bottom one of the bars P which will give the required space for the passage 35 of the strips, with the other projection upon the plate entered within that slot of the bar P which is next above the bottom bar, with the slot in which the projections of the plate are entered vertically in line with each other 40 and parallel to the vertical side of the strip t^7 . When this has been done, the plates p^3 are entered in slots of the bars P, which are vertically in line with the slots in which the plates P⁵ are located and so as to be parallel 45 with the vertical side of the strip t^7 , with the plates P⁵ preferably bounding that portion 50 of the strip-chutes C which are at the cutting end of the table T.

The letter K designates the knife by which 55 the tickets are cut from the strips as the latter slide downwardly in the slideways or chutes C. This knife K is provided with an arm A, formed integrally with the knife-shank a² and at right angles to the latter, and which 60 arm at each of its ends has formed in it a recessed cone-form bearing b', both of which latter are arranged so as to be centrally in alinement with the axis of said arm.

The letter E' designates an ear which is 65 outwardly projected from the side of the machine-frame, said ear having a journal-bolt J', provided with a nut N on its outer end, and

where threaded through said ear E' said bolt has on its end a cone-form journal V', adapted to enter one of the cone-form bearings b'. 70 The letter E² designates another ear which is also projected from the side of the machine-frame and provided with a journal-bolt J², having a nut N² on its outer end, said bolt being threaded into and through the ear E², 75 and where passing through the latter provided with a cone-form journal end V², adapted to enter that one of the cone-form recessed bearings b' of the arm A which is next adjacent. As thus constructed the knife K 80 when operated by its handle H can be actuated to rise and descend on its hinged connection. The letter E³ designates the cutting edge of the knife.

The letter I designates the metallic edge 85 of the lower end of the table T, with which the cutting edge E³ of the knife K makes a shearing engagement when operated to descend, and the letters B designate a strip-engaging bar which at one of its ends b² is 90 hinged to the machine-frame at that side of the latter which is opposite to that at which the knife is hinged. This strip-engaging bar B is shown as raised at Fig. 4.

The letters S' designates a V-form spring 95 which at one of its ends is rigidly connected to the top of the bar B at that end of the latter which is opposite to that at which this bar is hinged to the frame, as shown at Figs. 5 and 6. The letters S² designate another 100 spring having a leaf form, which at one of its ends is rigidly connected to the side of the machine-frame, as shown at Fig. 7, with its free resilient end S³ so placed that when the bar B is caused to descend on its hinged connection it will engage with and be so moved downwardly against the recoil force of this spring S².

The letters G designate a pin that is laterally projected from the side of the knife K 110 near the hinged connection which the latter makes with the machine side, as shown at Figs. 5 and 6, and when this knife is forced downwardly on its hinged connection this pin G engages with the spring S' to force it and the bar B downwardly against the recoil force 115 of said spring and also that of the spring S², with the under surface of the bar B bearing upon the top of the strips where resting upon the table T immediately above the cutting 120 edge I of the latter, to thus hold the strips while the tickets are being cut therefrom. When the knife K is raised, the spring S² becomes active to raise the bar B on its hinged connection, so as to permit the strips to again 125 descend to have the cutting operation repeated.

The letters M designate a gage by which the length of the tickets to be cut from the strips is regulated and by which the tickets 130 when cut from the strips are turned over in their descent to have them enter the assembling mechanism in proper position. This gage is shown in elevation at Fig. 8 and in

section at Fig. 3, and it is mounted upon two rods R R, of which there is one at each side of the gage, with the rods both in alinement with the inclination of the table T and each of them arranged to slide in a lug l, downwardly projected from the machine at each side of the table T, there being one of these connections shown at Fig. 7. Each of these rods R has formed on its top a ratchet R², and the letter a⁴ designates a shaft having bearings at a⁹ in each of the frame parts supporting the table T, as shown in Fig. 9.

The letters W' designate a gear-wheel mounted upon each end of said shaft a⁴ where extending beyond the bearings in which said shaft journals, with each of these wheels W' arranged to mesh into one of the ratchets R² that is on the same side of the machine as the gear-wheel.

20 The letter D designates a radially-graduated dial arranged upon and connected to one side of the table-supports back of one of the wheels W', with the shaft a⁴ passing through said dial.

25 The letter a⁵ designates a pointer upon that one of the wheels W' which is in front of the dial D and which is provided with a handle by which it can be moved, and thus operate the shaft a⁹ to operate the rods R, and thus 30 position the gage M relatively to the cutting edge of the table T as may be desired.

The letters I² I² designate two vertically-arranged studs by which the gage-plate m² of the gage M connects with the horizontally-35 arranged rods R R by means of a nut N³, threaded onto each of the studs beneath the plate m², and a jam-nut N⁴, threaded onto each of the studs where extended up through and above the top of the plate m², with the 40 lower ends of each of the studs I² connected to one of the rods R at l⁵. This gage M has a guiding-face g² formed by the beveled edge of the plate m² and a gage-face proper formed on the vertical side of the bar g⁴ at g³. This 45 bar g⁴ is connected to the top of the plate m² by the elliptically-formed springs S⁴ S⁴, of which there is one arranged at each side of said plate. These springs are at each of their inturned ends e⁴ connected to the top of the 50 plate m² at each side of the latter by means of a slot formed longitudinally in the inturned ends of each of the springs, (which slots are shown by dotted lines at Fig. 8,) a set-screw l⁶, provided with a collar l⁷, arranged to straddle the slot in each of the springs and to be 55 threaded into the plate m² below the spring, as indicated at l⁴, with the downturned end of each of the springs connected to the outer face of the bar g⁴ at g⁶. As thus constructed 60 and arranged the gage-face g³ of the bar g⁴ can be adjusted as to its distance away from the beveled guide-face g² of the plate m² and from the cutting edge I of the table T to adapt 65 the gage for the cutting of longer or shorter tickets.

The letter L designates a supplemental guiding and strip-supporting bar, having upon

its side next adjacent to the cutting edge L of the table T the beveled guide-face f³, said bar L being connected to the inner ends of two wires w⁴ w⁴, with each of the latter arranged to pass horizontally through a lug l⁷, depending from the under side of the plate m² at each side of the latter, with each of the lugs having a vertically-arranged set-screw m⁸ constructed to pass down through the plate m² and the lug to engage with the wire passing through it. As thus constructed the position of the guide-face f³ of the supplemental bar L may be varied as to its relative 80 distance from the cutting edge I of the table T and the gage-face g³ of the bar g⁴. It is the function of this supplemental bar L to have its guide-face f³ direct the end of the descending strip so as to have its lower end 85 abut against the gage-face g³ of the bar g⁴ and to have its flat top face f⁴ support the strip while being cut, and when the latter has been done to have the inclined face f³ operate to tumble or turn the ticket thus cut 90 from the strip while descending to the assembling mechanism. When cutting strips having a length considerably greater than their cross-measurement, this supplemental bar becomes a necessity to prevent the strip 95 from sagging between the gage-face g³ and the cutting edge of the table T; but where the tickets being cut have a length not much greater than their width the supplemental bar L may be dispensed and the gage M employed without it.

The letter U designates a table arranged below and in front of the table T to form a part of the ticket-assembling mechanism. This table U inclines downwardly as projected frontwardly, and at its upper end u² it is hinged to the machine-frame F.

The letter u³ designates a bar which at its inner end u⁴ is threaded into a projection O', offset from the front of the frame F, and therefrom this bar is extended upwardly and outwardly on an angle and provided with a head u⁵, on which this inclined table U rests.

The letter w⁶ designates a hand-wheel which is keyed to the bar u³ and by which the latter can be screwed into the projection O' to render the incline of the table U more acute to a perpendicular or screwed outwardly from the projection O' to render the inclination of the table less acute to a perpendicular. The upper surface of this table U is ruled off in inches and in sixths of inches in parallel lineation with the same parts of the scale upon the table T. The letters C² designate ticket chutes or slideways formed on the top of this table U, and the letters d designate partitions by which the sides of the ticket chutes or slideways are produced by the attachment of these partitions to the upper surface of this table U. One of these partitions d is shown in perspective and as detached at Fig. 10. The letters d² designate a spring arranged on the beveled upper end of each of these partitions d, each of which

latter connects with the table U by means of this spring d^2 , which is hooked onto the upper edge of the table U, by which connection and another connection made by means of a 5 clamping-spring S^6 , as will be hereinafter described, each of these partitions d is secured to the top of the table U.

The letter Y designates another table, which is arranged beneath the table U to form a part 10 of the ticket-assembling mechanism. This table Y has an upright and frontwardly-inclined rear end y^2 , which at y^3 is hinged to the side edges of the table U at their lower ends, as indicated at u^7 , with the bottom of the table Y supported upon a bar B^3 , which at b^5 is pivoted to the under side of the table Y, with the other end of this bar projected downwardly and inwardly on an angle to make a hinged connection h^6 with the vertical frame part F^6 , the latter being in front of and adjustably connected to the frame proper, F, by means of a slot m^8 , vertically formed in the frame part F^6 , and a set-screw T^6 , threaded into the frame proper, F.

25 The letter b^7 designates a turnbuckle arranged in the bar B^3 , by which the latter can be employed to give such inclination to the table Y as may be desired.

The letter y^6 designates a slot formed cross- 30 wise in the end plate y^2 at its bottom, as shown at Fig. 3.

The letters y^4 designate partitions, of which one is shown as detached at Fig. 11, and these partitions are connected to the upper face of 35 the table Y to form the ticket-assembling chambers A^3 . Each of these partitions y^4 has a laterally-projected lug y^8 on its inner end at the bottom adapted to enter the slot y^6 , and at its front end and at its bottom they 40 are each constructed with a laterally-extended projection y^7 and thereat provided with an L-form key k^3 , having its shank k^4 extended downwardly through said projection, so as to turn therein, and the shank at its upper end 45 having an operating-wheel w^8 and at its lower end provided with a laterally-extended foot k^5 , which when the key is turned by the wheel will underrun and engage with the bottom y^9 of the table Y to hold the partitions in position at its outer end. Each of the partitions 50 y^4 are cut away at their inner upper corners, as indicated at Fig. 11. This rounded-out and grooved portion of the upper inner corner of each of the partitions y^4 is designated 55 at n^4 , and the partitions d of the table U are each rounded out and grooved at d^4 , so that when the partitions d are in line with the partitions y^4 and one of the clamping-springs S^6 is sprung onto the lower end of each of the 60 partitions d , with the spring and rounded end of the last-named partitions entered within the cut-away portion n^4 of the partitions y^4 , the partitions of the tables U and Y connect, and the ticket-chutes C^2 of the table U will 65 connect with the ticket-assembling chambers A^3 of the table Y, with the connecting parts appearing as shown at Figs. 3 and 4. To fa-

cilitate the proper alignment of the ticket-chutes C^2 with the ticket-assembling chambers A^3 , the table Y is ruled off in a scale of 70 inches and sixths of inches in vertical parallel lineation with the scale upon the table U. The letters H^3 designate ticket-holders, of which there is one for each of the ticket-assembling chambers A^3 . One of these ticket-holders is shown as detached at Fig. 12 and in position at Fig. 3. They are preferably made of thin sheet metal, so as to have a horizontal bottom h^4 and an inwardly-inclined vertical end h^5 . Each of these partitions y^4 80 is notched in its upper edge at n^6 to receive a rod r^4 , with the latter arranged at right angles to these partitions y^4 to rest in any series of these notches which is desirable, the function of this rod being to retain the holders H^3 in a proper position to receive the descending tickets.

The mechanism thus described and illustrated is operated as follows: Strips of paper or cardboard having upon one of their faces the color which the tickets to be cut therefrom are intended to show are placed in the chutes C , of which any desired number may be employed that the width of the strips and the cross-measurement of the table T will permit. With the knife raised these strips will slide downwardly in the chute C , with their lower ends abutting to contact against the vertical gage-face of the gage M. The knife is then operated to descend, and which in so doing and before commencing to cut will force downwardly the bar B, causing the latter to engage with and hold the strips firmly upon the table T at and immediately above the cutting edge of the latter. When the knife has 105 by its descent cut the tickets from the ends of the strips thus placed between the cutting edge of the table T and the gage M, the knife and the bar B rises and the several tickets are by the beveled edge g^2 caused to turn over 110 in their descent by gravity to enter the chutes C^2 , through which they slide downwardly to be deposited in the holders H^3 of the ticket-assembling chambers A^3 , with the tickets all facing one way, and from which they are taken 115 and bunched to be used in the machine by which they are applied to sample cards. If desired, each of the chutes C may be used to deliver strips having a different color from the other chutes, or all of them may be made to 120 operate upon strips having the same color.

Having thus described my invention, what I claim, and desire to secure by Letters Patent, is—

1. In an apparatus for cutting color tickets 125 from strips of cardboard or paper the combination with an inclined table having at its lower end a cutting edge, and upon its upper face chutes arranged to be parallel to the table sides, in which chutes the strips will descend, of a gage arranged below the cutting edge of the table, in line with its inclination, against which the lower ends of the descending strips will abut; a holding-bar which at 130

one of its ends is hinged to the table side; a spring at one side of the table against the recoil of which said bar is operated to descend upon the strips; and a knife hinged to the table at one side of the latter, and which when descending to make a shearing engagement with the cutting edge of the table to cut the tickets from the strips, will in advance of such cutting movement, operate the holding-bar to descend upon the strips at, and immediately above the cutting edge of the table substantially as, and for the purposes set forth.

2. In an apparatus for cutting and assembling color tickets the combination with an inclined table provided with strip-chutes arranged parallel to the table sides, said table having a cutting edge at its lower end; of a gage arranged below the cutting edge of the table to be in line with the inclination of the latter; a holder-bar hinged to one side of the table and provided with a spring against the resiliency of which the bar can be forced to descend upon the strips; a knife hinged to the table at one of its sides, and adapted to descend and in its descent to make a shearing engagement with the edge of the table, and in advance of the latter action to move downwardly said holder-bar against the force of its spring; a beveled edge upon the gage; an inclined ticket-chute arranged beneath each of the strip-chutes, and vertically in line with the latter; a series of ticket-assembling chambers each provided with a ticket-holder, and each connected to one of the ticket-chutes, constructed and arranged to be operated substantially as set forth.

3. In an apparatus for cutting and assembling color tickets the combination with an inclined table provided with chutes in which the tickets will descend to be cut; a gage below the lower end of the table whereby the length of the tickets to be cut is measured; a knife arranged to make a shearing engagement with the lower ends of the table to cut the tickets; a beveled edge upon the gage by which the tickets after being cut are turned in their descent; an inclined ticket-chute arranged immediately beneath and in line with each of the strip-chutes; a series of assembling-chambers each arranged to connect with one of the ticket-chutes, and each provided with a ticket-holder, constructed and arranged to operate substantially as shown and described.

4. The combination with the table T, hinged at its lower end to the frame F, and at its upper end adjustably connected to the frame in an inclined position; of the bars P, which are let into the table at right angles to its sides and each provided with slots p^2 , that are parallel to the table sides and vertically in line with each other; the plates p^3 , and p^5 , adapted to connect with said slots substantially as described; the gage M, mounted upon the rods R, R, each provided with a ratchet R^2 , and having a slideway at each side of the table; the radially-graduated dial D, at each

side of the table; the spur-wheel W' , having a pintle-shaft centering upon the dial D; at each side of the table and arranged to mesh 70 into the ratchet R^2 , thereat; and the knife K, hinged to the machine-frame at one side of the table and adapted to make a shearing engagement with the lower edge of the latter substantially as and for the purposes set forth. 75

5. The combination with the inclined table T, having the ticket-chutes C, formed thereon substantially as described; of the gage M, mounted upon the rods R, R, so as to be adjustably moved toward or from the lower end 80 of said table; and having the same inclination as the latter; the gage-plate m^2 , having the beveled inner edge g^2 ; the bar g^4 , having the gage-face proper g^3 , said bar being adjustably mounted upon the gage-plate m^2 , by 85 means of the springs S^4 , S^4 ; and the knife K, which at one of its ends is hinged to the machine at one side of the table T, and adapted to make a shearing engagement with the lower end edge of the latter substantially as 90 and for the purposes set forth.

6. The combination with the adjustably-inclined table T, provided with means for the production upon its upper surface of the strip-chutes C, substantially as described; of the 95 gage M, mounted adjustably upon rods whereby it can be moved toward or from the lower end edge of said table, and having the bar g^4 , provided with the gage-face proper g^3 ; the supplemental strip guiding and supporting 100 bar L, having the inner beveled face f^3 , and top face f^4 , and adjustably mounted upon the wires w^4 , w^4 , and the knife K, hinged at one of its ends at one side of the table and adapted to make a shearing engagement with 105 the lower end edge of the latter substantially as and for the purposes set forth.

7. The combination with the inclined table T, adapted to have the strip-chutes C formed on its upper surface; of the gage M, arranged 110 below said table in parallel inclination; the knife K, hinged at one of its ends to one side of the table and adapted to make a shearing engagement with the lower end edge of the latter; the inclined table U, provided with 115 ticket-chutes C^2 , arranged below the lower end of the table T; the table Y, having formed thereon the ticket-assembling inclosures A^2 , each provided with a ticket-holder H^3 , and each at its upper end connecting with one of 120 the ticket-chutes C^2 , substantially as and for the purposes set forth.

8. The combination with the inclined table U, adjustably hinged to the frame F, at u^2 , of the partitions d , each provided with the 125 spring d^2 , at its upper end, and being rounded and grooved on its lower end at d^4 ; the inclined table Y, having a vertically-arranged inner end y^2 , and provided with a horizontal slot y^6 , immediately above the table Y, the partitions y^4 , each provided with a projecting lug y^5 , and at the bottom of its inner end, and notched and grooved at its upper rear corner at n^4 , and having a key k^3 , at its front

end; and a clamping-spring S^6 , constructed and arranged to connect the partitions d , at their front ends to the table, and to enter the groove formed in the notched corners n^4 , of 5 each of the partition-plates y^4 , substantially as and for the purposes set forth.

Signed at the city of Troy, New York, this

13th day of December, 1898, and in the presence of the two witnesses whose names are hereto written.
